(57) **CLAIM**

The ornamental design for recreational water device as shown and described.

DESCRIPTION

1. Recreational water device

1.1 : Perspective

1.2 : Perspective

1.3 : Left

1.4 : Right

1.5 : Front

1.6 : Back

1.7 : Top

The characteristic features of the design lie in the shape of the element for an inflatable waterpark as shown in the drawings.
